UNITED STATES PATENT OFFICE

BENJAMIN A. KLAPPER, OF CHICAGO, ILLINOIS, ASSIGNOR TO SPRAGUE, WARNER & COMPANY, OF CHICAGO, ILLINOIS, A CORPORATION

DISPLAY CASE

Application filed March 11, 1930. Serial No. 434,948.

This invention relates to display cases; and more particularly to display cases adapted to display food products.

An object of the above invention is to provide a display case of improved and simplified structure embracing means for illuminating and ventilating the interior of the showcase in such a manner as to prevent the accumulation of moisture by condensation, or otherwise, which would cloud or otherwise dim the glass panels through which inspection of the foods is made while at the same time preventing an undue heating of the food or other products on display.

15 A further object of the invention is to provide in conjunction with a display case of the character indicated, reflecting means adapted to augment the display.

20 Further objects will more particularly appear in the course of the following detailed description.

Two sheets of drawings accompany this specification as part thereof, in which like reference characters indicate like parts throughout, in which:

Figure 1 is a plan view of the display case;

Figure 2 is a vertical cross section taken on line 2—2 of Figure 1;

Figure 3 is a vertical transverse cross section taken on line 3—3 of Figure 2; and

Figure 4 is a fragmentary cross section taken on line 4—4 of Figure 3.

Referring to the drawings, the improved showcase comprises a main top part 1 supported in any suitable manner as by legs 2. The top 1 is provided with a plurality of spaced openings 3, with which are associated semi-spherical reflectors 4 secured to the under face of top 1. Each of the reflectors 4 carries a source of illumination, here illustrated as incandescent electric bulbs 5, which are connected to a suitable source of current by conductor 7. Each reflector 4 is further provided with air ports 6, through which air is admitted to pass upwardly around the electric bulbs 5 and through the openings 3 in the top 1.

Mounted on top 1 on suitable brackets 8 are deflector plates 9 preferably of translu-

cent glass. These plates 9 substantially cover all of the electric bulbs 5 so as to conceal same from direct view.

At some suitable spot on the top, here shown as the center, a fan 10 is mounted, here shown as an electric fan associated with its propelling motor. Sides 11 rest upon the top 1 and enclose the four sides supporting a table 12 spaced above the deflector plates 9 and fan 10. The side walls 11 are provided with a plurality of air ports 13, which air ports are preferably assembled with shields 14 secured to the inner faces of the walls 11. The table 12 is provided with spaced air ports 15, and intermediate the air ports 15 is provided with openings 16 for the reception of the food containing receptacles 18.

70 Preferably, and as here illustrated, the walls of openings 16 are provided with a shoulder 17 adapted to support the bottom of vessels 18. The vessels 18 are preferably of transparent material such as glass, so that the light from the bulbs 5 passing through 75 translucent shields 9 can also pass through the bottoms of vessels 18 and illuminate the contents thereof.

Supported on the top of table 12 are side walls 19 provided with air outlet ports 26, 80 and these walls 19 support a transparent top 20 of plate glass, or the like.

The walls 19 in effect form a frame for the glass top 20, and are preferably mounted on table 12, as by hinges 21, being secured in 85 closed position by a suitable latch 25.

A top cover 22 is also hingedly secured to table 12 in association with frame 19 and brackets 23, and the top 22 carries upon its inner face a mirror 24, so that when the top 90 22 is in a vertical position, the mirror 24 will reflect the contents of vessels 18.

95 By the means thus described, it will be apparent that the contents of the vessels 18 will be properly illuminated, and a constant stream of air will be circulated through the display chamber to prevent the accumulation of moisture therein which would tend to condense on and cloud the plate glass cover 21.

100 The contents in vessels 18 will be visible

directly through plate glass cover 21, and be reflected in mirror 24.

Various modifications in the precise construction and arrangement of parts will readily suggest themselves to those skilled in the art, but within the scope of the present invention.

Having thus fully described my invention, I claim:

10. 1. In a show case with a transparent top, a shelf partition spaced below the top to form an upper and a lower compartment, said shelf having an opening, a transparent container adapted to seat in the opening and be supported by the shelf, and illuminating means in the lower compartment, means for utilizing part of the heat from said illuminating means to prevent condensation on the top, and for venting the bulk of the heated air consisting of air inlets in the bottom of the case, air vents in the side walls of the case below and above the partition shelf, and passages through the shelf partition smaller than said vents to provide a circulation of air into and out of the lower compartment with the diversion of a small part of said heated air into and out of the upper compartment.
15. 2. The structure of claim 1 with a transparent deflector positioned in the lower compartment between the source of illumination and the shelf supported container.
20. 3. The structure of claim 1 with means within the lower compartment for creating a positive air circulation.
25. 4. The structure of claim 1 with a transparent deflector between the shelf supported container and the source of illumination, and means adjacent baffle for creating a positive air circulation.

40. In testimony whereof I affix my signature.

BENJAMIN A. KLAPPER.
